Merwin & Stewart.

UNITED STATES PATENT OFFICE.

GUSTAV JOHANNES NAGEL, OF NEW YORK, N. Y., ASSIGNOR TO GARRETT H. SMITH, INC., OF NEW YORK, N. Y., A CORPORATION OF NEW YORK.

CIGAR-BAND.

1,254,151.

Specification of Letters Patent. Patented Jan. 22, 1918.

Continuation of application Serial No. 83,271, filed March 10, 1916. This application filed May 8, 1917. Serial No. 167,159.

To all whom it may concern:

Be it known that I, GUSTAV JOHANNES NAGEL, a citizen of the United States, and residing in New York, county and State of 5 New York, have invented new and useful Improvements in Cigar-Bands, of which the following is a specification.

This invention relates to cigar bands, and particularly to the so-called gumless bands 10 which may be described as self-locking, adjustable bands that are adapted to be retained in place on the cigar by friction, only, without the employment of an adhesive of any kind.

15 There are many objections to the ordinary band that is held in place upon the cigar by the adhesive which secures the overlapping ends thereof together. Among the principal objections to these bands may be mentioned 20 the fact that they are unsanitary, particularly since they are usually moistened by the tongue of workers in a cigar factory who are notoriously susceptible to, and often become afflicted with, pulmonary or serious 25 blood diseases from various causes, and especially because of being confined in poorly ventilated, dust-laden atmospheres for long periods of time. In addition to the foregoing objections such bands are found to be 30 undesirable because of the tendency of the same to become united to the delicate wrapper of the cigar by the adhesive which accidentally runs over on to the wrapper. As a result when the band is removed, a portion 35 of the wrapper is torn off with the consequent serious injury to the drawing qualities of the cigar. In fact in many cases mutilation of the wrapper upon the removal of the present band is so serious as to render the 40 cigar virtually useless to the connoisseur.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference 45 characters designate the same parts in the several views, and in which—

Figure 1 is a plan view of a cigar band embodying my improvement;

Fig. 2 is a rear elevation of the same with the ends in interlocking position; and 55

Fig. 3 is a perspective view of the band with ends interlocking as shown in Fig. 2 showing a cigar about to be inserted therein.

Without unnecessary restriction as to the design of the band or label carried by the 60 band or the species of material which may be employed in constructing the band, I show in the drawings a suggestion of a design of a band comprising a label portion 1, 1', formed with integral straps 2, 2'. 65 Each strap terminates in a hook portion having lobes 3, 3', the medial line of the angle between the inner face of the hook and the adjacent margin of its respective strap being inclined at an angle of less than 45° 70 to the major axis of said strap. When, therefore, the ends of the straps are bent rearwardly, the lobes 3, 3', of the hooks are each slipped beneath the strap-portion carrying the other hook and the lobe on the 75 strap-portion unprovided with teeth will interlock with the teeth on the opposing arm.

Referring to Fig. 3 it will be understood how the lobes 3, 3', of the ends of the band are each passed beneath the main portion of 80 the strap corresponding to the opposite lobe, and then after being thus assembled the band is slipped directly upon the cigar, being made of a size to fit thereon snugly by friction. The cigar holding the band thus in extended 85 position, it is impossible for the band to become loose or lost from place for two main reasons, namely, first, the hooks cannot become released by contraction of the cigar because the cigar prevents such movement, 90 and, secondly, each of the lobes or extreme end portions of the hooks is gripped by friction beneath a strap portion of the band. By this expedient I produce a cigar label 95 band adapted to be easily and quickly applied where it will be held with sufficient security for all practical purposes and without the requirement for the use of any kind of paste or gum. I, therefore, reduce the cost of manufacture by eliminating the necessity for applying gum to the label, and, moreover, I obviate the aforementioned common source of complaint incident to the application of paste or gum to a cigar wrapper, such gum tending to damage the cigar or 100 render it otherwise objectionable.

The band can be easily adjusted to accommodate the varying sizes of cigars by merely causing the crotch of the hook on the strap unprovided with any teeth to engage the 5 particular tooth of the series of teeth 4 which will effect the desired adjustment of the band so as to enable it to snugly fit around the cigar. Otherwise, were no teeth provided to effect such adjustment, it would 10 seldom be possible to select a cigar which would be of the proper size to snugly fit within such non-adjustable band. Obviously, if desired, in lieu of saw-teeth, a series of blunt teeth may be employed without departing 15 from the spirit of the invention as broadly claimed herein.

This application is filed as a continuation of my co-pending application No. 83,271, filed March 10, 1916.

Having thus described my invention, what I claim and desire to secure by Letters Patent is:—

1. A cigar band comprising a central label portion, a pair of straps formed integral therewith and projecting therefrom at diametrically opposite points, the respective straps being each provided with an oppo-

sitely extending terminal hook, one of said hooks being adapted to lie beneath, and be gripped by, the strap portion carrying the other hook, when said band is applied in position upon the cigar, and one of said straps being provided on one of its lateral edges intermediate said hook portion and said label portion with a series of projecting 35 teeth.

2. A cigar band comprising a central label portion, a pair of straps formed integral therewith and projecting therefrom at diametrically opposite points, the respective 40 straps being each provided with an oppositely extending terminal hook, one of said hooks being adapted to lie beneath, and be gripped by, the strap portion carrying the other hook, when said band is applied in 45 position upon the cigar, and one of said straps being provided on one of its lateral edges intermediate said hook portion and said label portion with a series of inwardly inclined saw-teeth, the upper face of each 50 tooth sloping outwardly and downwardly.

Signed at New York, county and State of New York, this 5th day of May, 1917.

GUSTAV JOHANNES NAGEL.
